UNITED STATES PATENT OFFICE.

SYDNEY PRESTWICH, OF CINCINNATI, OHIO, ASSIGNOR TO THE AMERICAN LAUNDRY MACHINERY COMPANY, OF NORWOOD, OHIO, A CORPORATION OF OHIO.

CENTRIFUGAL EXTRACTOR.

Application filed October 16, 1917. Serial No. 196,826.

To all whom it may concern:

Be it known that I, SYDNEY PRESTWICH, citizen of the United States, residing at Cincinnati, in the county of Hamilton and State of Ohio, have invented certain new and useful Improvements in Centrifugal Extractors, of which the following is a specification.

This invention relates to centrifugal extractors, such as are used for extracting surplus water or liquids from goods or fabrics to be laundered or cleaned or from any other substance or materials. The invention is more particularly concerned with the rotating basket which carries the goods or materials to be extracted.

The object of the invention is to provide an improved extractor whose basket is so constructed as to enable the goods or materials to be readily loaded into said basket or unloaded therefrom, and which enables the basket to be operated with less than a full load.

Further objects of the invention are in part obvious and in part will appear more in detail hereinafter.

The invention comprises the extractor hereinafter described and claimed.

In the drawings, which represent one embodiment of the invention, Fig. 1 is a central elevation, illustrating the basket in its normal or running position with the discharge door in the curb closed; and Fig. 2 is a similar view, parts being omitted, showing the parts in discharge or unloading position.

The extractor shown in the drawings comprises a suitable curb 1 of the usual shape and provided in its bottom with a seat 2 for a step bearing 3 for the spindle 4 journalled at its upper end in a bearing 5 carried by an arm 6 attached to the upper end of standard 7 supported on the curb. On the spindle is the usual driving pulley 8 to receive the driving belt, and opposite said pulley is a brake 9 carried by a pivoted lever 10 connected by a link 11 to a lever 12 actuated by a screw handle 13.

The top of the curb is provided with a large opening 14, while its side wall is also provided with an opening 15 closed by a door or cover 16 hinged at the bottom of the opening and preferably provided within the curb with a depending flange 17. This door serves not only as a closure for the opening

15 but also as a discharge table along which the goods are moved into and from the basket as will appear.

On the spindle 4 is mounted the basket which carries the goods or material to be extracted. This basket comprises a conical bottom 18 attached to or integral with a sleeve 19 rotating with the shaft 4, said bottom and sleeve having attached thereto a series, four, for example, of radially extending vanes or partitions 20, whose upper outer edges are connected by a continuous ring 21. All of these parts rotate with the spindle 4 and have no vertical movement relative thereto.

The basket also includes an outer wall or rim 22 flaring downwardly and lying close to the outer edges of the vanes 20, said wall or rim being connected at its upper end to a cover plate having a circular or annular ring like portion 23 carried by a small sleeve 24 rotatable and slidable on the spindle 4 and provided at its upper end with an undercut flange 25.

At the upper end of the standard 7 is a bracket 26 carrying a shaft 27 on which is a driving pulley 28. Said shaft is also provided with a clutch member 29 rotating with said shaft and cooperating with clutch members 30 upon two oppositely disposed bevel gears 31 loose on said shaft and both meshing with a cooperating bevel gear 32 on the upper end of a screw shaft 33 threaded into a nut 34 in a follower 35, said follower being also provided with a sleeve portion 36 traveling vertically upon a non-rotatable guide shaft 37. Follower 35 is provided with depending brackets 38 in which is suitably mounted a rod 39 carrying at its forward end a head 40 provided with a hook member 41 and a handle 42 passing around the spindle 4 to the front of the machine.

Fig. 1 shows the driving or operating position of the parts. The vertically movable member of the basket, to wit, its outer wall and top, is down. The basket is presumed to be loaded. The door 16 is closed. The load may be distributed readily among the several compartments of the basket. A light load, for example, could be distributed equally between two opposite compartments, the remaining compartments being empty, without disturbing or affecting the balance of the basket. In this position power is sup-

plied through a belt to the pulley 8 to rotate the basket, thereby causing moisture or liquids which it contains to flow outwardly to the wall or rim 22 and then through the 5 same if it is perforate, or, if imperforate, down to the bottom of said wall and out through the spaces 43 between the bottom edge of said wall and floor of the basket. When extraction has been completed and the 10 basket brought to rest the vertically movable member of the basket is lifted to enable the goods to be discharged from the machine. This is done by pulling forwardly on the handle 42 to shift the hook member 41 into 15 position beneath the flange 25 of the sleeve 24. Next the clutch shifting lever 44 is shifted to throw the clutch member 29 into engagement with the proper one of the co-operating clutch members 30 and thereby rotate 20 the screw shaft 33 to lift the traveler 35 and movable member of the basket to the position shown in Fig. 2. Door 16 is then opened, and by turning the basket by hand to present its several compartments in turn 25 to the door opening, the goods therein can be dragged out over the door. The basket side wall and top are then lowered by reverse rotation of the screw shaft, and after loading the machine with a new batch and 30 closing the door the new batch can be extracted as before.

What I claim is:—

1. An extractor, comprising a basket rotatable on a vertical axis, said basket comprising a bottom fixed against vertical movement and a series of outwardly extending partitions having downwardly inclined outer edges, and a vertically movable outer wall on said basket arranged when lifted to expose the material therein, said outer wall flaring downwardly.
2. An extractor, comprising a basket rotatable on a vertical axis, said basket comprising a bottom fixed against vertical movement and carrying a series of upwardly extending vertical partitions connected at their upper edges by an annular member, and an outer wall on said basket movable vertically relative to its bottom.
3. An extractor, comprising a basket rotatable on a vertical axis, said basket comprising a bottom fixed against vertical movement and carrying a series of upwardly extending vertical partitions connected at their upper edges by an annular member and having downwardly inclined outer edges, and an outer wall on said basket movable vertically relative to its bottom, said outer wall flaring downwardly.
4. An extractor, comprising a rotatable vertical spindle carrying a basket, said basket having a bottom fixed against vertical

movement and outwardly extending partition members, a sleeve vertically movable on said spindle, and an outer wall on said basket carried by said sleeve, said outer wall flaring downwardly.

5. An extractor, comprising a spindle rotatable on a vertical axis, a basket carried thereby and having a bottom fixed against vertical movement, a series of upwardly extending vertical partitions for said basket, and an outer wall or rim vertically movable relative to the basket bottom.

6. An extractor, comprising an outer 75 curb or casing, a basket rotatable therein and having a bottom fixed against vertical movement, a vertically movable outer wall on said basket, and a movable door on the side of said curb adapted to close an open- 80 ing therein.

7. An extractor, comprising an outer curb or casing, a basket rotatable therein and having a bottom fixed against vertical movement, a vertically movable outer wall 85 on said basket, and a movable door on the side of said curb and adapted to close an opening therein, said door being movable into position to serve as a discharge table along which the material to be extracted 90 can be removed from said basket.

8. An extractor, comprising a basket rotatable on a vertical axis and having a fixed bottom, a vertically movable side wall and top for said basket, and outwardly extending vertical partitions in said basket fixed against vertical movement relative thereto.

9. An extractor, comprising a basket rotatable on a vertical axis and having a bottom fixed against vertical movement, a side 100 wall for said basket movable vertically relative to said bottom, a vertically movable traveler, and means for operatively connecting and disconnecting said traveler to and from said side wall.

10. An extractor, comprising a basket rotatable on a vertical axis and having a bottom fixed against vertical movement, a side wall for said basket movable vertically relative to said bottom, and a vertically movable traveler having readily detachable operative connection with said side wall.

11. An extractor, comprising a basket rotatable on a vertical axis and having a fixed bottom, a spindle supporting said basket, a 115 sleeve slidable vertically on said spindle, a side wall and top for said basket carried by said sleeve, a vertically movable traveler, and means for operatively connecting and disconnecting said traveler to and from 120 said sleeve.

In testimony whereof I affix my signature.

SYDNEY PRESTWICH.
